UNITED STATES PATENT OFFICE.

CHARLES MOORE, OF PHILADELPHIA, PENNSYLVANIA.

HYDRAULIC AIR-COMPRESSOR.

SPECIFICATION forming part of Letters Patent No. 309,642, dated December 23, 1884.

Application filed March 20, 1884. (No model.)

To all whom it may concern:

Be it known that I, CHARLES MOORE, of the city and county of Philadelphia, in the State of Pennsylvania, have invented a new 5 and useful Improvement in Hydraulic Air-Compressors, of which the following is a specification.

My invention relates to a hydraulic air-compressor in which is employed a compression-chamber provided with valves for the escape of compressed air and the inlet of uncom- 10 pressed air, and in which a float is so combined with water inlet and delivery valves that water, under pressure, from any suitable source 15 of supply is first admitted to the compression-chamber to expel the air therefrom, and is subsequently exhausted from said chamber, to allow the latter to again fill with air of at- 20 mospheric pressure. In such an apparatus 25 there is also employed a supplemental or relief valve, which is opened at the end of compression to allow a small quantity of water to escape, in order to thus lower the pressure of the water and enable the large or main water- 50 outlet valve to open easily.

In my apparatus the above-mentioned supplemental or relief valve is held open after the main water-outlet valve is opened, and serves as an air-inlet valve, it being arranged 55 near the upper part of the compression-chamber.

My invention consists in various novel combinations of parts and details of construction in an apparatus of the kind above referred to, 35 and will be hereinafter described, and pointed out in the claims.

In the accompanying drawings, Figure 1 represents a vertical section of an apparatus embodying my invention, the parts being in the 40 positions occupied at the end of compression, and the supplemental or relief valve for the escape of water being open. Fig. 2 is a vertical section on the plane of the dotted line $x-x$, Fig. 1. Fig. 3 is an irregular horizontal section on the plane of the dotted line $y-y$, Fig. 1. Fig. 3* is a detail view hereinafter described; 45 and Fig. 4 is a sectional elevation very similar to Fig. 1, illustrating the parts in the positions which they occupy at the instant the 50 water-inlet valve is opened and the inlet air-

valve and supplemental or relief valve is closed.

Similar letters of reference designate corresponding parts in all the figures.

In this example of my invention the compression-chamber consists of a base-piece, A, and a casing or box, A', mounted thereon and bolted thereto in an air-tight manner. Upon the casing A' is formed a dome or upward extension, A², at the top of which is located 55 the discharge - valve for compressed air. Screwed into the top of said dome portion or upward extension is a plug or bonnet, a, containing an internal passage, a', at the lower end of which is shown a valve, b, serving as 60 a check to prevent the escape of water upward through the air-outlet. At the upper end of the passage a' is located an upwardly-opening air-valve, c, which is held down by a spring, c'. Upon the cylindric exterior of the 65 plug a is fitted an annular piece or collar, d, held in place by an inclosing-cap, d', and air entering the said cap d' passes downward through the passages * and into an annular groove, **, in the collar d, from which it passes 70 to the compressed-air outlet d".

B C designate the water-inlet pipe and outlet or exhaust pipe which enter the base-piece A of the compression-chamber, and D designates a rocking valve-carrying arm of pecu- 75 liar construction, which controls the water-inlet.

E designates an inwardly-opening exhaust-valve, which is hinged at e, and closes by gravity on the inner end of the water outlet 80 or exhaust pipe or passage C.

G designates a float on a float-lever, G', fulcrumed at e', in a frame, H, which has a water-tight connection with the base-piece A.

From the water-inlet B a passage, e², extends 90 through the frame H, as best shown in Figs. 2 and 3, and terminates in a valve-seat, e³, presented in a vertical plane, as shown in Fig. 3. The valve-carrying arm D is fulcrumed at f in the frame H, and swings be- 95 tween the two surfaces e³e⁴. (Shown in Fig. 3.) In the arm is fitted a short section of tube, e⁵, which is of a length to snugly work between the valve-seats e³e⁴, and constitutes the water-inlet valve, and when the arm is brought to 100

the position shown in Figs. 1 and 3 the tube or valve proper, e^5 , is full opposite the seat e^6 , and the water-inlet through the passage e^2 is closed, so that no water can enter the compression-chamber A'. The arm D and water-inlet valve e^5 are then nearly or fully balanced. When the arm D is swung to the position shown in Fig. 3*, which corresponds to the position in Fig. 4, the tube-section e^5 is exposed beyond the seat e^6 , and consequently water enters the compression-chamber A' under pressure. The tube-section e^5 is loosely fitted in the rocking arm D, and can be renewed when worn out.

15 In the upper part of the arm D is an opening, f^1 , through which passes a rod, f^2 , extending across the frame H, and having upon it a rubber sleeve or tube, f^3 , forming a cushion which limits the opening and closing movements of the arm D, and prevents any shock in arresting it at either end of its movement. The upper end of the arm D is angular—that is, it is formed by reverse inclines—as best shown in Figs. 1 and 4, and on said inclines bears a roller, g , which is flanged to hold it against lateral displacement, and is carried by one end of a spring, G^2 , attached at its other end to the lever G' . When the float G is in its elevated position, (shown in Fig. 1,) the water-inlet valve e^5 is closed, and as the float falls the roller g runs up the front incline on the top of the arm D.

20 25 30 35 30

On the float G reaching its lowermost position (shown in Fig. 4) the roller g passes the angle between the two inclines, and by bearing on the rearmost incline tilts the arm D forward into an open position. (Shown in Fig. 4.)

As before stated, the water-outlet or exhaust-valve E closes by gravity, and must be opened against the pressure of water in the chamber A', whatever that may be.

Upon the frame H is fulcrumed at h a lever, I, which carries at its upper end a roller, i , in the same vertical plane as the arm D, and to the lower end of said lever is attached a tensile spring, i' , which exerts a pull thereon. From the lever I an arm, i^2 , projects behind the main outlet-valve E, and in said valve is an adjusting-screw, i^3 , against the end of which said arm bears, as shown best in Figs. 1 and 2. When the pressure of the valve-carrying arm D on the upper end of the lever I is removed by the closing movement of the valve-carrying arm D, the spring i' , acting on the lever I, effects the movement of the lever and the opening of the valve E. When the lever I is acted upon by the arm D in its opening movement, it is drawn back against the force of the spring i' , and the valve E is allowed to close by gravity. The valve E is therefore self-closing.

In the same vertical plane as the rocking arm D is a lever, J, carrying at its upper end a valve, j , which serves to control an aperture, j' , leading from the chamber A', and which is screwed into the lever, so that it may be ad-

justed therein. The lever J is fulcrumed at j^2 , and at its lower end is provided with a roller, j^3 , against which the rocking arm D strikes and bears when it is moved back to the position shown in Fig. 1, thereby serving to hold the valve j from the seat j' .

Attached to the lever J is a spring, j^4 , which serves to automatically close the valve when its operation is not resisted.

In the chamber A' is a passage, k , extending downward to the exhaust-passage C in said base-piece, and open at its upper end.

On the exterior of the chamber A' is a small chest, forming a passage, l , which is secured by a screw, l^2 , and which forms a communication on the outside of the chamber A' between the opening or port j' and a corresponding opening or port, k' . Consequently, when the valve j is open, air may pass through the passage k , the port k' , passage l , and port j' , and into the compression-chamber A'; or water may pass from said chamber in a reverse direction and downward to the main exhaust or outlet passage or pipe C. It will therefore be seen that the valve j controls the passage of water or air through the ports and passages $j' l k' k$.

The operation of my apparatus is as follows: The float-lever G' and float G are supposed to be in their lower position (shown in Fig. 4) and the inlet-valve e^5 is open. At the same time the relief and air valve j is closed by its spring j^4 , the rocking arm D being away from the roller j^3 , and the spring i' cannot pull the lever I to open the outlet or exhaust valve E, because of the rocking arm D bearing against the roller i and precluding action of the lever. The water entering through the inlet-valve e^5 gradually compresses the air in the chamber, and when the latter attains sufficient pressure to open the air-outlet valve the compressed air is discharged. During the rising movement of the float G the roller g attached thereto runs over the inclined upper end of the rocking arm D, and as soon as it passes the highest point the roller comes onto the forward incline and shifts the rocking arm backward to the position shown in Fig. 1, thereby shutting off the supply of water and leaving the compression-chamber full of water at a pressure equal to the pressure of the air discharged.

During the upward movement of the float the valve b rests upon the guard-plate b^2 in its lowermost position; but as the float completes its upward movement it acts upon the stem of the valve b and raises the latter so as to entirely shut off the air-discharge, thus preventing water from passing up into the air-discharge, in case the water-inlet valve, for any reason, fails to operate. When the rocking arm D is swung backward to close the valve e^5 it recedes from the roller i ; but the spring i' cannot pull back the lever I and through the pin or arm i^2 open the outlet-valve E, because of the pressure in the chamber acting against the large area of the said valve. The back-

ward or closing movement of the rocking arm D carries it against the roller j' , thereby rocking the lever J and carrying the valve j away from its seat j' . The opening of the port j' 5 allows a portion of the water in the compression-chamber to escape through the passage l , opening or port k' , and passage k downward to the main outlet-pipe C, and as soon as the escape of water relieves the pressure in the 10 compression-chamber to a sufficient extent the spring i' pulls open the main exhaust or outlet valve E and affords provision for free escape of water. When the valve j has performed its function as a relief-valve it does not 15 close, because it is held open by the rocking arm D, and during the discharge or exhaust of water from the chamber the air enters the chamber through the passage k , opening or port k' , outside passage, l , and opening or port j' . As the float reaches its lowermost position its roller g swings forward the rocking arm D, thereby allowing the spring j' to close 20 the relief and air valve j , and at the same time the rocking valve, in its forward movement, 25 acts on the roller i and throws over the lever I, to permit the outlet or exhaust valve E to close. The water then enters through the inlet-valve e^s and the former operation is repeated. 30 The combination with the rocking arm D, having a cam-like back, of the spring-supported roller g , is very desirable as the valve remains inactive, fully open or fully closed during nearly the whole movement of the 35 float, and is shifted instantaneously at each end of the float's movement.

What I claim as my invention, and desire to secure by Letters Patent, is—

1. The combination, with a compression-chamber provided with inlets and outlets for 40 water and air, of a rocking arm carrying the water-inlet valve, and having a cam-like top consisting of reverse inclines, a float and a float-lever, and a spring-supported roller connected with said float-lever and bearing upon 45 the cam-like top of the said rocking arm, substantially as and for the purpose herein described.

2. The combination, with a compression-chamber provided with water and air inlets and outlets, of the rocking valve-carrying arm D and water-inlet valve, the said arm having 50 reverse inclines at its top, the float and float-lever G G', and the spring G², attached at one end to said float-lever and at the other end provided with the roller g , substantially as herein described.

3. The rocking valve-carrying arm D, fulcrumed at f , and having its top formed with 55 reverse inclines, and a water-inlet valve, e^s , consisting of a tube-section detachable from said arm, in combination with seats e^s e' , between which said valve e^s works, substantially as herein described.

60 4. The combination, with a compression-chamber provided with water and air inlets

and outlets, of a water-inlet valve and float-actuated mechanism for operating it, and a combined water-relief and air-inlet valve, and 70 passages controlled by said valve and communicating with the water-outlet and atmosphere, whereby water may be allowed to escape when the chamber is filled under pressure, and air allowed to enter to empty said chamber of water, substantially as herein described. 75

5. The combination, with a compression-chamber provided with air and water inlets and outlets, of a water-inlet valve and float-actuated mechanism for operating it, a combined water-relief and air-inlet valve, and a 80 pivoted lever carrying said water-relief and air-inlet valve, having its lower end in contact with the arm of the water-inlet valve, and adapted to be acted upon by said arm in its closing movement to open and hold open said 85 relief and air-inlet valve during the discharge of water from said chamber, substantially as herein described.

6. The combination, with a compression-chamber provided with water and air inlets 90 and outlets, and also provided with the passage k , the ports or openings k' j' , and the passage l , connecting said ports or openings k' j' , of a combined relief-valve and air-inlet valve, j , controlling said port or opening j' , a water-inlet valve and valve-carrying arm D, and means through which it acts to open said relief and air valve and to hold it open during the discharge of water from said chamber, and 95 float-actuated mechanism for operating said water-inlet valve, substantially as herein described.

7. The combination, with a compression-chamber provided with water-inlets and water-outlets, of the rocking valve-carrying arm 100 D, fulcrumed at f , and having reverse inclines at its top, the float and float-lever G G', and the spring-supported roller g for actuating 105 said valve-carrying arm, the lever J, the relief and air valve j upon said lever, and the spring j' , for returning said lever and closing the valve j when released by said arm D, substantially as herein described. 110

8. The combination, with a compression-chamber provided with water and air inlets 115 and outlets, of a valve-carrying arm, D, and water-inlet valve, float-actuated mechanism for operating said arm, a relief-valve through which water may escape at the end of compression, and means, as lever J, lever I, and 120 spring i' , through which the opening of the water-outlet and relief valves is controlled by the movements of said arm D, substantially as herein described.

9. The combination, with a compression-chamber provided with water and air inlets and outlets, of a valve-carrying arm, D, and water-inlet valve, float-actuated mechanism for operating said arm, a water-outlet or discharge valve, and means, as lever I and spring 125 i' , through which the opening of said water-outlet or discharge valve is controlled by the 130

movements of said arm D, substantially as herein described.

10. The combination, with the compression-chamber and its water inlet and outlet, of the 5 valve E, the rocking valve-carrying arm D, and water-inlet valve, and float-actuated mechanism for operating said arm, the lever I, upon the upper end of which the arm D acts, and

the lower end of which is arranged to act upon said outlet-valve to open the latter, and the 10 spring i', acting upon said lever I to open said outlet-valve, substantially as herein described.

CHARLES MOORE.
